UNITED STATES PATENT OFFICE.

JAMES H. RUSSELL, OF MANISTEE, MICHIGAN, ASSIGNOR OF ONE-HALF TO LEWIS S. RAMSDELL, OF MANISTEE, MICHIGAN.

CLOTHES-PIN.

1,279,010.

Specification of Letters Patent. Patented Sept. 17, 1918.

Application filed May 31, 1917. Serial No. 171,981.

To all whom it may concern:

Be it known that I, JAMES H. RUSSELL, a citizen of the United States, residing at Manistee, in the county of Manistee and 5 State of Michigan, have invented certain new and useful Improvements in Clothes-Pins, of which the following is a specification, reference being had therein to the accompanying drawing.

10 This invention relates primarily to wooden clothes-pins and has special reference to pins which are reinforced to prevent splitting.

15 A principal object of the invention is to associate with a clothes-pin made, say, of wood, means which will prevent the normal tendency of the pin to split at the head-portion thereof.

20 Another object of the invention is to provide a wooden clothes-pin with a reinforcing device, preferably of metal, which is so constructed as to embrace the pin along lines at right-angles to the slot in which the device is disposed and in a direction parallel to the usual line-receiving slot.

25 A subsidiary object of the invention is to provide, as an article of manufacture, a reinforcing device, preferably of metal, comprising a body-portion and two pin-engaging portions extending from the body-portion at an angle thereto, the angulated portions being preferably of a thickness less than that of the body-portion.

30 The invention in general seeks to provide 35 a clothes-pin which includes a structure that, from an operative standpoint, will, in practical use, possess a high degree of strength and durability and which, structurally considered, will be of great simplicity.

35 Other objects and advantages of the device will be obvious from the accompanying drawings, while still other will be pointed out in the following description.

40 The invention resides broadly in the features of construction and relative arrangement of the parts thereof, all as exemplified in the construction hereinafter set forth.

45 In order that the invention may be clearly 50 comprehended, drawings illustrating one of the possible embodiments and utilizations of the same are hereto appended as a part of this disclosure; it being understood that these drawings are merely illustrative and 55 that other embodiments and utilizations,

employing the underlying principles of the invention, fall within the spirit thereof and within the objects contemplated thereby.

In these drawings:

Figure 1 is a view in perspective of a 60 clothes-pin constructed in accordance with my invention;

Fig. 2 is a view in front elevation thereof;

Fig. 3 is a similar view illustrating a tension-varying feature of the structure, one 65 position of the parts being illustrated in full lines, and another position thereof appearing in dotted lines; and

Fig. 4 is a detail view, on an enlarged scale, of the reinforcing device detached 70 from the pin.

Referring particularly to these drawings, the reference-numeral 1 designates, generally, a clothes-pin which, in this particular instance, is made of wood and is provided 75 with the usual line-receiving slot 2 which divides one portion of the pin and presents spaced-apart prongs or members 3. The pin may be of any required dimension and form; but, in this example, it is shown as 80 cylindrical in form.

The pin is likewise formed with a second slot 4, preferably disposed at right-angles to the line-receiving slot, and extending, by preference, below the upper end of the line- 85 receiving slot, as shown.

Adapted to be disposed in the slot 4 and to occupy a position at the bottom thereof, is a reinforcing device 5. This comprises a body-portion 6, preferably having flat sides, 90 from which extend wings or pin-engaging portions 7, preferably of a thickness less than that of the body-portion. These wings, preferably and as shown, are curved so as to conform approximately with the curved surfaces of the pin to the end that they may more rightly embrace such surfaces and thereby have their efficiency correspondingly increased. It will be noted that the body- 95 portions of these wings are practically the same width-dimension, and are considerably wider than the thickness-dimension of the device.

When the reinforcing device is in its normal position in the slot provided for it in 105 the pin, the wings extend considerably beyond the edges of the slot and toward the line-receiving slot 2. By reason of the fact that these wings are of substantial width and length, they embrace a considerable (but 110

not the entire) portion of the surface of the pin between the line-receiving slot. Moreover, they so embrace said portions as to cause a limiting effect on the outward spreading movement of the same when the line is being forced up into its slot 2. The device, thus, becomes efficient to prevent the normal tendency of the pin to split along a plane corresponding to the line-receiving slot; and, in fact, affords such reinforcement thereof as to provide a pin of greater strength than ordinary wooden pins. Moreover, by reason of the thinness of the wings on the device, provision is thereby made for varying the amount of tension that may be applied thereon by the prongs while being spread apart. Moreover, according to the position of the device in the slot, this tension on the prongs may be varied, that is, increased or decreased. When the device is pushed down in the slot, the tension is increased; whereas, when it occupies a position somewhat higher up, the tension is lessened.

25 I am aware of the fact that it has heretofore been proposed to provide reinforcing devices for clothes-pins; but so far as I am aware, it is new to provide a device of the particular character herein illustrated which has the function of firmly bracing and reinforcing the weaker portion of the pin but, also, to effect a varying and spreading of the prongs according to the position which it occupies in its slot.

30 35 From the foregoing, it will be perceived that I have devised a clothes-pin which is well adapted to achieve the several objects and ends in view; and that the structure thereof is simple in form and efficient in use.

What I claim is:

1. A clothes pin provided with a line receiving slot extending into the pin from one end thereof, and with a brace receiving slot extending into the pin from the other end thereof.

45 2. A clothes pin provided with a line receiving slot extending into the pin from one end thereof, with a brace-receiving slot extending into the pin from the other end thereof, and a brace member disposed in one of said slots.

50 55 3. A clothes pin provided with a line receiving slot extending into the pin from one end thereof, with a brace-receiving slot extending into the pin from the other end thereof, a brace member having a body portion adapted to be disposed in the brace-receiving slot, and extended portions adapted to embrace a portion of the pin.

60 65 70 4. A clothes pin provided with a line receiving slot extending into the pin from one end thereof, with a brace receiving slot extending into the pin from the other end thereof, and communicating with the line receiving slot, a brace member having a body portion adapted to be forced into the brace receiving slot from the end opposite the line receiving slot and disposed at the point of communication between the slot, and extensions on the body portion adapted to embrace a portion of the pin, and extending in opposite directions to a point adjacent the line receiving slot.

75 In testimony whereof I affix my signature in presence of two witnesses.

JAMES H. RUSSELL.
